ATTORNEY

UNITED STATES PATENT OFFICE.

LUCIAN ROSENWALD, OF KANSAS CITY, MISSOURI.

FLOWER SUPPORT.

Application filed October 30, 1926. Serial No. 145,207.

My invention relates to devices for supporting flowers, and has for its principal object to provide a device of this character for use in supporting flowers in vases of 5 diverse shapes and dimensions, whereby a single device may serve with equal efficiency in various situations, and variations of a preferred form may be produced for specific situations, the present invention being an 10 improvement on those disclosed in Letters Patent No. 1,491,925 and No. 1,491,926, issued to me on April 29, 1924.

In accomplishing my object I provide a flower support comprising a base on which 15 the spaced screens are mounted. The base is preferably of relatively small diameter, and is adapted by shape, thickness, material and other characteristics to fit into receptacles of various forms, such as vases, flower 20 bowls, dishes, urns, baskets, boxes and the like, and seating on the bottom of a receptacle to constitute the foundation upon which the screen members are erected. The spaced screens are joined by any suitable means, 25 a preferred form being unitary construction of a multiple plane, perforated element, and are supported on the base by a pedestal that may be integral with the perforated element and that is adaptable to space the said element 30 from the base. I provide for a multiplicity of variations in the manufactured form of the device, and for interchange of parts, particularly the use of a holder of any desired design with standardized bases 35 as will appear in the description. In addition therefore to the advantages of use, I provide by my device advantages in manufacture whereby the cost of production is low, and flower supports of the desired types 40 and characters, and separate holders and bases, may be made conveniently and economically available to the public.

I have shown in the drawings several variations in detail of structure, all using 45 my invention, but I do not wish to be understood as limiting my invention to application only to the variations displayed, the drawings being illustrative of method of application of the principles of my preferred structure.

In the drawings:

Fig. 1 represents my device as installed in a bowl and functioning in the supporting and anchoring of flowers.

55 Fig. 2 is a disassociated perspective view

of the device, the principal elements disassociated.

Fig. 3 is a modified form of the base element.

Fig. 4 is a perspective view from below 60 of a modified form of my device.

Fig. 5 is a cross sectional view of the modified form shown in Fig. 4.

Referring in detail to the drawings:

1 is a base, comprising a body 2 which 65 may be of a desired shape and a bearing portion 3 preferably integral with said body and constituting a longitudinal member thereof, the bearing portion being provided with a slot constituting a socket 4. 70

A flower holder 5 is provided comprising a plurality of perforated members 6, upper and 7, lower, said perforated members consisting preferably of wire mesh screens as shown, although perforated plates may be 75 used; mesh spreaders 8 and preferably spring spreaders 9 being provided securing and connecting the perforated members together in spaced relation. A horizontally elongated pedestal 10 extending downwardly 80 on the longitudinal axis of the lower screen 7 and connected with said screen is adapted to project into socket 4 thereby effecting engagement with base 1, the co-operation of base and pedestal sustaining the holder in 85 a horizontal position, the pedestal spacing the holder from the bottom of bowl 11 in which the device may be placed for the purpose of supporting flowers 12 as disclosed in Fig. 1. 90

Legs 13 are provided for the holder 5 extending in desired directions and distances from the holder, adapted to serve as braces therefor, and shown in Fig. 2 as depending from lower perforated member 7 and 95 aligned with the pedestal. The legs may, however, be positioned in any relation to the holder that conditions of use may suggest.

In my preferred use of wire mesh for the 100 construction of the holder 5 of my device, and as specifically illustrated in Fig. 2, I prefer to prepare a wire mesh screen having a width equal to the desired length of the contemplated holder, and having a length 105 slightly in excess of the transverse periphery of the holder plus the height of the pedestal. I bend the wire mesh along spaced parallels that mark the width of the upper perforated member relatively at right angles 110

downward, thus forming mesh spreaders 8; then bending said wire mesh on parallels marking the lower edges of the spreaders relatively at right angles inwardly to form the lower perforated member 7. The overlapping ends of said wire mesh are then bent downwardly adjacent the axis of the lower perforated member, the depending ends of mesh being brought together to form a unitary flange, portions of which are cut away, the cutting process producing the longitudinal limits of the pedestal 10 and legs 13, the dimension of pedestal and depending legs shown in their projection from the holder being considered as height. I show in Fig. 3, 4 and 5 modified forms of details of my device which I will now describe, referring also to details already mentioned and to my modifications of the same. In Fig. 3, the bearing portion 3 of the base 1, previously described as having a socket, is shown as an elongated transverse shoulder 14 projecting upwardly from the base, and the base is pictured as ring-like. Using such a modification, additional lateral bracing of the holder by the pedestal projected into the slot is attained when such bracing is desirable. The shoulder may serve as a spacing factor for the holder, the pedestal in such case being itself spaced from the bottom of the bowl, the shoulder supporting the holder and its upper surface constituting ledges 15 on which said holder is stabilized. In Fig. 4 a ring-like base is disclosed having the specified bearing member 3, the under surface of which is here continuous. This modified form is used when another modification of detail is availed of, namely, the permanent attachment of pedestal 10 to the bearing member.

Fig. 4 also discloses modifications in the details of spreaders 8 and 9, the wire mesh screen in this case being prepared, in anticipation of such modified form, as having lateral ears of suitable extension adapted to be bent downwardly to constitute supplementary spreaders 8^a, the lower edges of which may be attached to lower perforated member 7 as at 16 to provide additional rigidity for the holder and to produce a holder completely enclosed by its spreaders and thus providing additional anchorage facilities for the stems of the flowers. The said spread-

ers may be adapted for various functions, and I particularly set forth the adaptability of spring spreader 9, by means of extending a resilient loop, to serve as a means of preventing lateral movement of the device when in functional situation.

What I claim and desire to secure by Letters Patent is:

1. A flower support comprising parallel spaced screens and a spreading screen formed from a single sheet of material, and a pedestal connected with said screens for supporting the holder.
2. In a flower support, a base, and a holder comprising parallel vertically spaced horizontal screens and means connecting the screens, said lower screen comprising a member having an integral pedestal portion engageable with the base for supporting the holder in spaced relation to the base.
3. A flower support comprising a base having a transverse elongated slot, a flower holder including a screen, and a horizontally elongated pedestal connected with said holder for mounting in said elongated base slot to support the holder in horizontal position.
4. In a flower support, a flower holder comprising spaced parallel screens, a horizontally elongated pedestal connected with the screens, and a base having a slot to receive the pedestal and a shoulder to receive the holder for supporting the same.
5. In combination with a vase, a device for supporting flowers in the vase including a base, a holder including a screen and a pedestal mounted on the base for supporting the screen in spaced relation with the vase, and legs integral with said holder and extending therefrom for engagement with the vase to stabilize the holder.
6. In combination with a vase, a flower support comprising a base having a slot, a holder including a screen adapted for support in horizontal position in the vase, a pedestal connected with the holder and adapted to seat in said base slot for supporting the holder, and bracing members including legs depending from said holder in alignment with the pedestal and adapted to engage the vase to stabilize the holder in supported position.

In testimony whereof I affix my signature.
LUCIAN ROSENWALD.
